UNITED STATES PATENT OFFICE.

HENRY J. MARTIN, OF CHICAGO, ILLINOIS, ASSIGNOR TO THE WHITMAN & BARNES MANUFACTURING COMPANY, OF AKRON, OHIO.

DESIGN FOR A WRENCH-JAW.

SPECIFICATION forming part of Design No. 28,487, dated April 19, 1898.

Application filed June 23, 1897. Serial No. 643,313. Term of patent 14 years.

To all whom it may concern:

Be it known that I, HENRY J. MARTIN, a citizen of the United States, residing at Chicago, in the county of Cook and State of Illinois, have invented and produced a new and original Design for a Wrench-Jaw, of which the following is a specification, reference being had to the accompanying drawings, forming part thereof.

Figure 1 is a front, Fig. 2 a side, and Fig. 3 a rear, elevation of the wrench-jaw embodying my new design.

The leading or material feature of my design consists in the configuration produced by the peculiarly-shaped wrench-jaw shown

in the drawings, the essential features of which are the two corrugated faces *a* and *b*, of substantially equal length, making substantially a right angle with each other, the semicircle *c*, and the faces *d d* at each side thereof, substantially as shown.

Having described my invention, what I claim as new, and desire to secure by Letters Patent, is—

The design for a wrench-jaw as herein shown and described.

HENRY J. MARTIN.
